UNITED STATES PATENT OFFICE

137,290

DESIGN FOR A MATERNITY GOWN

Bertha C. Waters, Kansas City, Kans.

Application December 16, 1943, Serial No. 112,012

Term of patent 14 years

To all whom it may concern:

Be it known that I, Bertha C. Waters, a citizen of the United States and resident of Kansas City, in the county of Wyandotte and State of Kansas, have invented a new, original, and ornamental Design for a Maternity Gown, of which the following is a specification, reference being had to the accompanying drawing, forming part thereof, in which Fig. 1 is a front elevation of a maternity gown, showing my new design. Fig. 2 is a rear elevation of the same. Fig. 3 is a front elevation of a portion of the maternity gown, showing the left shoulder strap unbuttoned and in a stretched out position.

I claim:

The ornamental design for a maternity gown, as shown.

BERTHA C. WATERS.
